PAVED OR SIMILAR RAILWAY STRUCTURE

Application filed April 27, 1929. Serial No. 358,522.

The result of engineering experience and research on the subject of paved railway structures leads to the conclusion which is generally accepted that an uniformly controlled resilient rail bearing gives the most efficient and economical service with the minimum of noise, rail corrosion and deterioration and hence the minimum requirement for repairs to paving, rolling stock and rails.

Because of the rigidity of the car wheels and the relative rigidity of the rolling stock, the highest obtainable degree of resiliency in the rail bearings is necessary, and any increase in the effective tie bearing area gives a corresponding increase of the life of the structure and of the effectiveness in the way of ease of riding and absence of destructive vibration of the cars. Steam roads are in almost all instances so constructed as to give a resilient bearing for the rails and in the construction of street railways, the majority of which are paved railway structures, the same effect is sought. This type of construction includes wooden ties spaced apart and laid on concrete, broken stone and in some instances on the natural soil, a more substantial subbase being, however, considered necessary in the majority of instances.

These paved railways include a concrete paving base extending from a few inches above the ties to a bottom surface which is near the bottom surface of the ties. Unless the rails are supported directly on the portions of the paving base between the ties, which obviously tends to break down the paving base due to the shock and vibration and because there is usually a pocket or joint in the concrete between the ties, the entire load of the cars on the rails is transmitted through the ties to the soil or other subbase. The ties usually rest on about thirty-three per cent. of the roadbed and on account of the shrinkage of the concrete between them they work loose, and due to the car impact they sink into the subbase to varying depths so that the track structure, i. e., the rails and ties, constitute a structure which is separate from the paving base and supported independently of the paving.

As already suggested, the only connection between the concrete paving base on the two sides of the rail is immediately under the rail and between the ties and in laying the concrete at this point voids or pockets usually occur under the rail, and if the concrete on the two sides of the rail is placed successively, there is also an open joint under or nearly under the rail in addition to the pockets. So it is not practical to support the rails on the paving base.

The method commonly used to overcome this difficulty is to place four to ten inches of broken stone, slag, sand or gravel between the ties and the subsoil, and not infrequently a concrete slab is placed below these materials.

These methods are expensive and are not always effective. To accomplish the desired result, the material beneath the ties must be tamped and this can not be accomplished in a uniformly satisfactory manner. The wider the tie the more the uncertainty and difficulty involved, either in hand or mechanical tamping. There is always an element of uncertainty as to what percentage of the tie has a bearing on the tamped material below it and further as to what percentage of the total tie area has a bearing on this material after several months or years of use involving more or less continuous car impact.

The usual rectangular wooden tie in common use in street railway structures is 6" x 8" x 8' and spaced 24" on centers. The maximum bearing area of this tie on the subbase is 5.3 square feet or thirty-three per cent. of the total subbase area. As already pointed out, it is not practical to tamp uniformly under these ties, and, because of the car traffic, they necessarily settle and on account of the uneven tamping they settle unevenly and in settling remove a portion of the support beneath the pavement and cause breaking of the pavement as it yields to the action of the truck wheels and other heavy traffic.

These various difficulties are overcome and the necessity for subbases irrespective of the

natural subgrade is eliminated by the improved railway structure of the invention.

Assuming for purposes of illustration the same amount of wood or any suitable resilient material in the tie, the same amount of concrete in the base and the same spacing in the improved railway structure, the bearing area of each tie on the adjacent concrete is 9 square feet. In the improved structure the bearing surface of the tie is so arranged that the car impact is transmitted from this bearing area or any bearing area which may be provided, to the adjacent concrete base instead of all to the subgrade, and this concrete base, i. e., so much of it as combines with each particular tie, has a bearing area on the subgrade of 13.4 square feet or three-fourths of the total base as compared to a bearing area of 5.3 square feet of the tie on the subbase according to the present existing practice. The above statement of the improved practice assumes that the tie is supported in the concrete base practically free of the subbase, otherwise one hundred per cent. instead of seventy-five per cent. of the area of the bed and ties would constitute the bearing area. It is not essential, however, that the ties have no direct bearing on the subbase or entirely supported by the wedging action to be described.

In accordance with the preferred form of the invention, the railway structure includes a concrete bed or base, which extends from a few inches above the ties to a bottom level which is near the bottom of the ties. In order to produce the result outlined and transmit the load on the ties to the concrete base which is ordinarily the paving base instead of directly from the bottom of the tie to the subbase, thus making a continuous integral railway structure comprising the ties, rails and bed, the load on the rails being transmitted to the ties and from the ties to the concrete base and hence to the soil or subbase as aforesaid instead of directly from the ties to the subbase; the ties which are thus embedded in the concrete base are given a tapering or wedge shaped outline in transverse cross section, i. e., the longitudinal side surfaces, are inclined downwardly and inwardly and preferably the ties are also tapered in a plane at right angles to the rails, being likewise of downwardly reduced cross section so that the ends are inclined inwardly and downwardly toward the center of the tie. In this way the side and end surfaces of the ties are caused to bear most effectively on the adjacent surfaces of the concrete, the downward thrust of the carload being transmitted in a more nearly horizontal direction or directions to the concrete by the wedging action of the ties, the incline or taper being preferably but slight so that the load is applied to the concrete in the form of longitudinal and preferably lateral compression stresses

which are resisted most efficiently, the harmful stresses or cantilever action, including tension elements, being almost completely eliminated.

By thus giving the ties which may be of wood or any suitable material a slight bevel or downward taper and embedding them closely in the concrete bed, the two are combined in a single structure, which utilizes to best advantage the resilience of the ties and the compressive strength of the concrete, distributing the load over the entire area of the material below them, and affording for the rails a uniformly resilient support whereby the downward thrust of the car load is distributed over the entire area of the base and applied uniformly to the soil or other subbase throughout this area.

In the accompanying drawings I have illustrated a paved railway structure embodying the features of my invention in the preferred form.

In the drawings:

Figure 1 is a section of the railway structure of the invention taken at right angles to the rails and showing a portion of a tie in elevation and the paving and base in section.

Figure 2 is a section at right angles to the plane of Figure 1, taken on the line 2—2 of Figure 1.

Figure 3 is a top line view of the paved railway structure.

Figure 4 is a perspective view of one of the ties which is a feature of the invention.

Referring to the drawings by numerals, each of which is used to indicate the same or similar parts in the different figures, the railway structure as shown comprises a concrete paving base 1 on which the drawings show a pavement 2, though the base 1 may be any suitable bed of concrete not necessarily serving as a paving base. The structure also includes railway ties 3, embedded in the base, which preferably extends a few inches above the ties as shown and terminates in or near the plane of the bottom of the ties. In accordance with the illustration, the entire railway structure, including the concrete bed 1, the ties 3, and the usual railway rails 4, supported on the ties, rests and is supported on the soil 5, for which any suitable subbase may, of course, be substituted, though the structure of the invention is regarded as eliminating all necessity for such a subbase.

In order to effect an interlocking of the ties with the base so as to form an integral railway structure, comprising the base, ties and rails as already outlined utilizing the resiliency of the ties and the compressive strength of the concrete, whereby the load or carload on the rails is resiliently supported on and transmitted to and distributed throughout the base or the portion thereof between the adjacent ties, the ties are con-

structed of a tapering cross section in a vertical plane extending in a direction parallel to the rails, the front and rear longitudinal surfaces 6 and 7 of the ties being downwardly and inwardly inclined toward the central line or central vertical plane of each tie and preferably as already pointed out, the ends of the ties at 8 are also downwardly and inwardly inclined, producing a similar downward taper in the vertical section of the tie taken transversely to the length of the rails and longitudinally of the tie. The plane of the latter section is indicated by the line 10—10 in Figure 3, the plane of the transverse section. Figure 2, being indicated by the line 2—2 in Figure 1.

The illustration includes incidentally a wheel 20 of a street car or other rolling stock, and paving guards 21 and 22 on each side of the rail to support the edges of the pavement, these paving guards in the form of the invention shown being held in position by anchor members 24 embedded in the paving base 1. Between the guards 21 and 22 and the rail 4 I have shown a plastic filler 25 and 26 on the opposite sides of the rail to seal the joints and prevent the entrance of water between the rail and the concrete paving base. This is necessary or at least desirable in the localities where freezing occurs to prevent destruction of the concrete due to the expansion of the water in freezing within the structure.

In order to produce the result outlined, the concrete which is to compose the base 1 is carefully tamped between the ties and against the ends if the tapered ends are used and preferably the portion of the base near and between the ties which actually receives the weight therefrom, the same being indicated by reference character 11, is made thicker than the remainder of the paving base at 12. To effect the desired result the soil or other subbase, as already outlined, is preferably cut away beneath, between and in the vicinity of the ties 3, forming a longitudinal shoulder 14, on each side of the roadbed spaced outwardly a few inches from the ends of the ties, which shoulders form a shallow trench confining the concrete at each outer edge of the thickened portion forming the railway bed 11 and providing for effective tamping of the concrete against the inclined end surfaces 8 of the ties. This result may, however, be effected in any suitable manner and the shape of the base is not essential. In this way the inclined surfaces of concrete 15, bearing on the ends of the ties, and 16 and 17 bearing against the front and rear downwardly and inwardly inclined longitudinal surfaces 6 and 7, are formed and when the concrete has hardened these surfaces 15, 16 and 17 of the concrete form a rigid support for the tie, having in this way a wedging action which permits the tie to yield to a slight degree rela-

tively to the concrete. The yielding of the tie in this way and the downward yielding of the portion of the tie immediately beneath the rail gives the controlled resilient support to the rail already suggested. The downward yielding of the ties is only such as results from shrinkage and compression of the wood due to the load. This compression takes place both in a vertical direction and in the direction of the thickness of the wedge sections. The wedging action described which is due to this yielding, while it is sufficient to support the ties, is such as to transmit to the concrete, forces as the result of the downward impact of the rail which are mainly forces of compression exerted almost longitudinally and most easily and efficiently resisted by the concrete. When the ties have thus yielded or been compressed to the wedge shaped seats in the concrete formed by the moulding of the concrete about the ties, the combined structure may be accurately described as continuous and integral. In fact, the yielding of the ties by compression in this way is so slight as to be almost imperceptible, being sufficient only to apply the load placed upon the ties to the combined surfaces of the concrete and wood. The shrinkage of the concrete which is also taken up by the settling of the ties is apt to be greater.

I have thus described specifically and in detail a continuous integral railway structure comprising resilient ties of downwardly tapering cross section with rails resiliently supported on the ties and a concrete base or bed closely fitted as by tamping between the ties connecting and supporting them by the wedging action of the inclined surfaces forming the taper which transmits the load or a considerable portion of it to the concrete base mainly in the form of compression stress distributing the weight or load on the rails thus received throughout the concrete by which it is transmitted with substantial uniformity to the soil or any surface or sub-base upon which the base may be laid. While the ties and rails are preferably thus supported entirely by the wedging action, the construction is capable of considerable variation within the broader conception of the invention, and it is not essential that the ties be supported out of contact with or independently of the subbase or entirely by the wedging action, and while the description is specific and in detail, the specific terms herein are used descriptively rather than in a limiting sense, the scope of the invention being defined in the claims.

What I claim as new and desire to secure by Letters Patent is:

1. The combination in a paved railway structure of resilient ties having a downward taper, rails supported on the ties and concrete between the ties and conforming to the taper whereby the concrete is caused to support the

ties, the load on the rails being transmitted through the ties to the concrete by the wedging action of the tapered ties.

2. The combination in a railway structure of resilient ties having a downward taper in both the longitudinal and transverse cross sections and concrete in which the ties are embedded, the concrete being arranged in close contact with the sides and ends of the ties, and rails supported on the ties whereby the load on the rails is transmitted from the ties to the concrete by the wedging action of the taper, the rails, ties and concrete forming a continuous integral structure.

3. The combination in a railway structure of resilient ties having a downward taper in both the longitudinal and transverse cross sections and a concrete base in which the ties are embedded, the concrete being placed in close contact with the sides and ends of the ties and rails supported on the ties whereby the load on the rails is transmitted from the ties to the concrete by the wedging action of the taper, the rails, ties and concrete base forming an integral structure, by which the car impact is transmitted with substantial uniformity to any suitable subgrade.

4. The combination in a railway structure of resilient ties having substantially plane side surfaces converging downwardly, rails supported on the ties and concrete in which the ties are embedded, the concrete having surfaces parallel to and in close contact with the said converging surfaces whereby the concrete tends to support the ties and the carload by the wedging action of the ties transmitting the load thereto.

5. The combination in a paved railway structure of resilient ties having substantially plane side surfaces converging downwardly, rails supported on the ties and concrete in which the ties are embedded, the concrete extending from a few inches above the ties to a bottom level near the bottom level of the ties and having surfaces parallel to and in close contact with the said converging surfaces whereby the concrete tends to support the ties and the carload by the wedging action of the ties transmitting the load thereto.

6. A railway base or bed composed of downwardly tapered resilient ties spaced apart and an oppositely tapered concrete portion between each pair of adjacent ties and engaging each said tie, the tapers compensating for each other so that the ties and concrete form a combined continuous structure and a non rigid subbase supporting said structure, rails bearing on the ties only and forcing them down, the contact between the ties and the concrete being close enough to support the ties on the concrete.

7. A railway base or bed composed of downwardly tapered resilient ties spaced apart having an oppositely tapered concrete portion between each pair of adjacent ties,

the corresponding surfaces of the ties and concrete being in close engagement and the depressions compensating for each other so that the ties and concrete form a continuous structure, and a non-rigid subbase supporting said structure and railway rails bearing on the ties and forcing them down until the wedge contact between the ties and concrete becomes close enough to support the ties on the concrete.

Signed by me at Baltimore, Maryland, this 24th day of April, 1929.

WILLIAM S. GODWIN.
